CLAIM

The ornamental design for a container bag with multiple sealable locks and pocket, as shown and described.

DESCRIPTION

FIG. 1 is a perspective view of a first embodiment of the container bag with multiple sealable locks and pockets; FIG. 2 is a front view thereof; FIG. 3 is a side view thereof; FIG. 4 is a front view thereof, illustrating that the detachable connection portion between the two pockets has been torn apart to separate the two pockets to form two bags; FIG. 5 is a perspective view thereof, illustrating one of the sealable locks is in opened condition; FIG. 6 is a perspective view thereof, illustrating that the detachable connection portion between the two pockets is tearing apart to separate the two pockets; FIG. 7 is a perspective view of the second embodiment of the container bag with multiple sealable locks and pockets; FIG. 8 is a front view of FIG. 7; and, FIG. 9 is a front view of FIG. 7, illustrating that the detachable connection portion between the two pockets has been torn apart to separate the two pockets to form two bags. The broken line portion of the figure drawings is included to show unclaimed subject matter only and forms no part of the claimed design.
